UNITED STATES PATENT OFFICE

VICTOR PETERSEN, OF OMAHA, NEBRASKA

DOOR SILENCER DEVICE

Application filed February 18, 1930. Serial No. 429,356.

This invention relates to door silencers and has particular relation to a device adapted for use primarily in connection with doors within a dwelling house.

An object of the invention is to provide a means whereby noises attendant, as heretofore practiced, upon the opening and closing of doors will be eliminated.

Another object of the invention is to provide a device adapted for the above described purposes which may be installed within a door opening and particularly in alignment with a door stop in a manner whereby the clothing of persons passing through the door opening will not become caught upon the device.

A further object of the invention is to provide a device which is economical in construction, easy of installation and certain of operation.

Other and further objects and advantages of the invention will be understood from the following detailed description, reference being had to the accompanying drawings in which:

Figure 1 illustrates a fragmentary horizontal sectional view of a door jamb, its casing and a door, certain parts thereof being broken away, and showing the new device installed in a position of use, the latter being in section.

Figure 2 is a side elevation of the jamb and having the new device applied to the stop therefor, the view being taken at right angles to the showing in Figure 1.

Figure 3 is a longitudinal sectional view of the new device.

Figure 4 is an end view thereof, and

Figure 5 is an end view opposite to the view and showing in Figure 4.

Referring to the drawings wherein like numerals of reference indicate like or corresponding parts throughout the several views, 10 indicates a door jamb and 11 the side casings thereof. In accordance with the conventional practice the fixtures for the door opening and the door 12 includes a door stop 13, within which the new device 14 is adapted to be positioned in a manner whereby one of the side edges is flush with the stop 13, and

also the front thereof is flush with the edge of the stop.

The new device comprises a body portion 15, which is provided with a front flange 16, and a rear flange 17, such flanges being bent substantially at right angles to said body portion 15.

Intermediate said flanges, a cylindrical member 18 is carried. The cylinder 18 is hollow and is adapted to be retained between said flanges by any suitable means, such as by means of an indented concentric shoulder 19 formed upon the flange 16 and by means of providing a shoulder 20 upon the member 18, said shoulder being adapted to be received within an aperture 21 formed through the flange 17.

An aperture 22 is formed through the flange 16 and is adapted to snugly receive a plunger 22', the latter being provided with a shoulder 23 for preventing a too great sliding movement of said plunger within said aperture in a manner whereby the said parts would become disengaged.

The plunger 22' is provided with a rubber bumper 24 and is adapted to be normally urged outwardly of the device by means of a spring 25 carried within the hollow cylindrical member 18.

A cap 26 is threadedly received within the cylinder 18 in a manner whereby the spring 25 is prevented from outward movement.

The cap 26 is provided with a bit slot 27 for the reception of a screw driver for the purpose and function of adjusting the tension of the spring 25 to suit the individual requirements of a door.

In the operation and practice of the invention, the device is preferably installed, flush with a stop 13 as shown in the drawings and secured to the door jamb by means of screws or keepers 28.

When the door 12 is closed against the stop, it will first encounter the bumper 24 of the new device, and on account of the tension of the spring 25, the latter will prevent the door 12 from "slamming" and producing annoying noises to the occupants of the dwelling house.

It will also be understood that when the

bolt of the lock or keeper mechanism is received within the strike, the latter being secured to the jamb, that the normally outwardly urged bumper 24 will register against the door 12 in a manner whereby said bolt will firmly engage the strike, thereby preventing rattling noises of the door such as is occasioned by draughts of air, and the like.

In operation, and assuming that the door 10 12 is large or of heavy material such as oak, the tension of a spring 25 may be adjusted in a manner whereby the plunger 22 will not readily retire within the cylindrical member 18, and with the result that an occupant of 15 the dwelling upon closing a heavy door, or slamming it, cannot produce unnecessary noises.

Similarly for light doors or small doors formed of western pine, the tension of the 20 spring 25 may be adjusted to suit any particular condition required.

From the foregoing description, it is thought to be obvious that a door silencer constructed in accordance with my invention is 25 particularly well adapted for use by reason of the convenience and facility with which it may be assembled and operated, and it will also be obvious that my invention is susceptible of some change and modification without 30 departing from the principle and spirit thereof, and for this reason I do not wish to be understood as limiting myself to the precise arrangement and formation of the several parts herein shown in carrying out my invention 35 in practice, except as herein claimed.

What is claimed is:—

1. A door silencer comprising a casing composed of a plate and flanges on the plate, one of the flanges being perforated and having a pressed-in part around the perforation, 40 a tube between the flanges registering with the perforation and confined by said pressed-in part, and a yieldably-pressed plunger in and projecting from said tube and perforated 45 flange.

2. A door silencer comprising a plate having spaced flanges, one of said flanges having an opening, a tube having a reduced and shouldered end engaged in said opening and 50 against the flange, and a yieldably-pressed plunger in and projecting from said tube.

3. A door silencer comprising a plate having flanges with aligned openings, a tube held between the flanges registering with the openings, a plunger in the tube projecting through one opening, a spring in the tube behind the plunger, and a cap threaded in the opposite 55 end of the tube through the opening in the other flange and acting to adjust the tension 60 of said spring.

4. A door silencer comprising a plate having flanges, means to secure the plate to a door jamb, a tube between the flanges, one of the flanges having an opening of less diameter than the tube forming a stop shoulder, a

plunger in the tube having a reduced and socketed end received through the opening and a shoulder to engage the stop shoulder, a resilient tip in the socket and spring means in the tube to force the plunger outwardly.

In testimony whereof, I have affixed my signature.

VICTOR PETERSEN.
